C. C. GUERNSEY.
NON-REFILLABLE BOTTLE.
APPLICATION FILED OCT. 30, 1907.# UNITED STATES PATENT OFFICE.

CHARLES C. GUERNSEY, OF DERRY, NEW HAMPSHIRE, ASSIGNOR OF ONE-FOURTH TO
GEORGE A. PORTER AND ONE-FOURTH TO GEORGE PROCTOR, BOTH OF BOSTON, MASSACHUSETTS.

NON-REFILLABLE BOTTLE.

No. 892,252.

Specification of Letters Patent.

Patented June 30, 1908.

Application filed October 30, 1907. Serial No. 399,921.

To all whom it may concern:

Be it known that I, CHARLES C. GUERNSEY, a citizen of the United States, residing at Derry, in the county of Rockingham and State of New Hampshire, have invented certain new and useful Improvements in Non-Refillable Bottles, of which the following is a specification.

In devising bottles of the type adapted not to be refilled it is desirable to dispense with springs and yet provide means to positively hold the valve seated when the bottle is turned to an approximately horizontal position and to a point slightly beyond the horizontal, so as to preclude a partial refilling of the bottle by immersing the same in the liquid to be stored therein while holding the bottle in or nearly a horizontal position.

This invention provides a lock for the valve of peculiar formation, the neck of the bottle having an inner beveled shoulder with which a loose weight of approximately pear or ovoidal shape co-operates.

For a full description of the invention and the merits thereof and also to acquire a knowledge of the details of construction of the means for effecting the result, reference is to be had to the following description and accompanying drawings.

While the invention may be adapted to different forms and conditions by changes in the structure and minor details without departing from the spirit or essential features thereof, still the preferred embodiment is shown in the accompanying drawings, in which:

Figure 1 is a vertical central section of the upper portion of a bottle, illustrating the application of the invention. Fig. 2 is a view of the parts shown in Fig. 1, illustrating the relation of the valve and lock device co-operating therewith when the bottle is tilted to a position slightly beyond the horizontal. Fig. 3 is a detail perspective view of the guard.

Corresponding and like parts are referred to in the following description and indicated in all the views of the drawings by the same reference characters.

The bottle or like receptacle 1 provided with a neck has the latter flared or bulged at a point between its ends. A valve section 2 is secured in the inner end of the neck and is provided at its upper end with a flared

opening forming a seat 3 against which snugly fits the conical valve 4. The section 2 is formed with an outer shoulder 5 against which abuts a packing 6 slipped upon the lower end of the section and designed to provide a tight joint between said section and the neck of the bottle and which packing may consist of a ring of cork, rubber or other suitable material. The valve 4 is buoyant and may be formed of cork or other light material; and by being made conical it readily seats itself and insures the formation of a tight joint. A plate or disk 7 is fitted to the upper end of the valve and has its edge portion projecting beyond the sides thereof to overlap the upper end of the valve section 2. Disks or plates 8 and 9 are spaced apart and have connection with each other and with the valve and plate 7 and are supported by means of a stem 10 which may form a part of the valve or be fitted thereto in any manner. The stem 10 projects some distance from the lower end of the valve and acts in a measure to direct the valve to its seat and to prevent turning thereof when the bottle is tilted to pour off the contents. The parts 7, 8 and 9 may be of wood or other light material of less specific gravity than water so as to float therein. By having the valve and connecting parts of buoyant material the valve will automatically seat itself should an attempt be made to fill the bottle by inverting the same and immersing it in liquid.

The neck of the bottle flares slightly from the valve section and terminates in a shoulder 11 which is beveled or converged and the neck above the beveled shoulder 11 gradually converges to a straight portion, which latter receives the guard 12. The neck below and adjacent to the beveled shoulder 11 is slightly enlarged, as shown at 13, to receive the butt of the weight 14 and which butt is of a size to touch the beveled shoulder 11 at one point and an edge portion of the plate or disk 8 so as to form a lock to hold the valve seated, as indicated most clearly in Fig. 1. The weight 14 is of pear or ovoidal shape and is of a length to have its points touch the neck at a point above the shoulder 11 and diametrically opposite to the point of contact of the butt with the neck and part 8. The weight 14 may be of any material of a specific gravity greater or less than water.

When the weight is of less specific gravity than the amount of water displaced thereby, 110

it will coöperate with the valve to force the same to its seat, when the bottle is inverted and immersed in a liquid. The pear or ovoidal shape of the weight and its relative length to the opening through the neck insures the weight assuming a position with its major axis inclined to the horizontal and with its point elevated, hence the weight touches the neck at diametrically opposite points and the part 8 of the valve at an intermediate point, thereby forming a lock to hold the valve securely seated.

The guard 12 is hollow and consists of a shell closed at its inner end and open at its outer end, the latter being provided with an outer flange 15 to enter a rabbet or enlargement at the outer end of the neck so as to limit the inward movement of the guard when placing it in position. Corresponding grooves are formed in the opposing sides of the guard and neck to form a space to receive cement 16 or like material. A groove 17 is formed in a side of the guard and communicates with the annular groove and provides a passage by means of which the cement may be supplied to the annular space when the guard is in position. The lower portion of the guard is made slightly smaller or of less diameter than the upper portion to provide a space 18 between it and the neck of the bottle to admit of the liquid contents passing to and through the openings 19 when the bottle is tilted to pour off the contents of the bottle. The openings 19 are inclined in an upward and outward direction from their lower ends to prevent a wire reaching the valve or the weight 14. A packing 20 is slipped upon the reduced portion of the guard and abuts against a shoulder formed at the base thereof and obtains a tight joint between the guard and neck so as to prevent any of the cement or like material passing into the bottle when filling the space formed by the companion grooves of the neck and guard.

Having thus described the invention, what is claimed as new is:

1. In a bottle or like receptacle provided with a neck, the combination of a downwardly closing valve arranged within the neck of the bottle, and an oblong weight located in the neck and coöperating with the valve to form a lock therefor, said weight

normally occupying a position with its major axis inclined to the horizontal and said weight touching the neck at opposite points and exerting a pressure upon the valve at an intermediate point.

2. In a bottle or like receptacle provided with a neck, the combination with a valve located in the neck and adapted to close downward, and a weight arranged within the neck and having an approximate pear or ovoidal form and normally occupying a position with its point upward and touching the neck at opposite points and exerting a pressure upon the valve at an intermediate point.

3. In a bottle or like receptacle provided with a neck, the latter bulged at a point between its ends and provided with an inner shoulder, a downwardly closing valve located at the inner end of the neck, and a weight of approximately pear or ovoidal shape adapted to exert a pressure upon the valve to hold the same seated and touching the neck at diametrically opposite points and exerting a pressure upon the valve at an intermediate point, the butt of the weight obtaining a bearing against the shoulder of the neck and the point of said weight coming in contact with the neck above said shoulder.

4. In a bottle or like receptacle provided with a neck, the latter enlarged intermediate of its ends and having an inner shoulder, a downwardly closing valve at the inner end of the neck, a plate or disk having connection with the upper portion of the valve, and an oblong or pear shaped weight normally forming a lock to hold the valve seated by exerting pressure upon the said plate and abutting against said shoulder.

5. In combination, a bottle or like receptacle provided with a neck having an inner shoulder, a downwardly closing valve having upper and lower spaced plates or disks, and a weight of approximately pear form adapted to hold the valve seated and normally in contact with the neck at diametrically opposite points and with the upper disk of the valve intermediate of said points.

In testimony whereof I affix my signature in presence of two witnesses.

CHARLES C. GUERNSEY. [L. S.]
Witnesses:

ALONZO E. YONT,
GEORGE PROCTOR.
